UNITED STATES PATENT OFFICE.

MICHAEL J. MURRAY, OF NEW YORK, N. Y.

MANUFACTURE OF ARTIFICIAL TOOTH-CROWNS.

1,058,381.

Specification of Letters Patent.

Patented Apr. 8, 1913.

Application filed February 25, 1911. Serial No. 610,794.

To all whom it may concern:

Be it known that I, MICHAEL J. MURRAY, a citizen of the United States, and resident of the borough of Manhattan, in the city and State of New York, have invented a new and useful Improvement in the Manufacture of Artificial Tooth-Crowns, of which the following is a specification.

This invention relates to certain improvements in the manufacture of artificial tooth crowns and consists in an artificial tooth crown having a cavity therein provided with an unglazed lining and the method of producing the same.

In the accompanying drawings, Figure 1 represents in top plan a portion of a mold bar showing one way of introducing a coating of non-glazing material into the cavity of an artificial tooth crown. Fig. 2 is a similar view showing another way of introducing the coating of non-glazing material into the cavity in the tooth crown. Fig. 3 is a section taken in the plane of the line A—A of Fig. 1, Fig. 4 is a section taken in the plane of the line B—B of Fig. 2. Fig. 5 is a section taken in the plane of the line C—C of Fig. 3, Fig. 6 is a section taken in the plane of the line D—D of Fig. 4, Fig. 7 is a longitudinal section from front to rear taken through a completed artificial tooth crown, and Fig. 8 is a plan view of the completed artificial tooth crown, looking toward the base thereof.

The artificial tooth crown is denoted by 1. Its cavity in the base 2, for receiving a pin or other fastening means, is provided with a lining 3 of unglazed material, such, for instance, as silex.

One method of carrying out my invention is to coat a fusible pin 4 carried by the mold bar 5, with a non-glazing material, such, for instance, as silex, and introduce the so coated portion of the pin into the cavity in the tooth crown, so as to bring the material into contact with the walls of the cavity before the tooth crown is burned. The parts

are then inserted into a furnace for burning the tooth crown and this operation will also burn the non-glazing material into the cavity and form an unglazed lining therefor to 50 which cement may be permanently united when used for securing the tooth crown to the part to which it is to be attached.

Another way of introducing the coating of non-glazing material into the cavity in 55 the tooth crown before it is burned, is by inserting a fusible cylinder 6 covered with a coating of non-glazing material, over a non-fusible pin 7 projecting from the bar 5 and then inserting the pin with its coated fusible cylinder into the cavity in the tooth crown before the crown is burned. The parts are then inserted into a furnace where the tooth crown is burned and the fusible cylinder is burned away, thus leaving the 65 cavity provided with an unglazed lining suitable for the attachment of the cement as above described.

It is to be understood that the above are only two of the ways that the cavities in 70 the tooth crown can be coated preparatory to the burning of the tooth crown.

What I claim is:

The method of forming an artificial tooth crown with the walls of its cavity provided 75 with a coating of unglazed material, such as silex, consisting in coating a fusible element with a non-glazing material and introducing the same into the cavity before the crown is burned and then burning the crown for 80 burning the non-glazing material into the walls of the cavity and destroying the fusible element.

In testimony, that I claim the foregoing as my invention, I have signed my name in 85 presence of two witnesses, this twentyfirst day of February 1911.

MICHAEL J. MURRAY.
